(54) **SHEARING MACHINE, HORIZONTAL**

(76) Inventor: **Thomas Blanchard**

Thomas Blanchard of the City, and State of New York.

Letter Patent.

The subject-matter referred to in these Letter Patent and making part of the same, containing a description in the words of the said Thomas Blanchard himself of his horizontal shearing machine.

The invention of this improvement in machinery for shearing cloth, called the horizontal shearing machine consists in the construction, the moving horizontal shear is so to have it moved back and forth in the operation of cutting, with two cranks in an axis, with a crank near each end, together with the other necessary parts constructed in the manner required for this machine. A proper wooden frame about three feet high and as wide as the cloth intended to be generally sheared may require, is made of good hard timber, having its bottom sills framed together which receive and support two posts which all the operating parts of the machine such as shears, rollers, rolling brush, beams, band, wheel, shafts, slot and crop bars, are fixed. To complete this frame two crop beams are fixed on the outside of said posts about sixteen or twenty inches from each sills and to the ends of these crop beams which may be three feet long or more are fixed, first the rolling beams on which the cloth to be sheared is first wound & at the other ends of said crop beams is fixed the axis containing the cranks to give motion to the shear, at crop bar is also put through said posts from side to side being at right angles and at the middle of said outside crop beam, and secured in said posts with wedges, upon the upper edge of this crop bar the edge of the upper and stationary shear rests, that is when shearing the cloth passes between the edge of the stationary shear and the upper edge of this crop bar, which supports the said

shear, the edges of said crop bar must be straight.

This stationary shear is a flat plate of steel as long as the width of the cloth may require and about three inches wide having at each end a gudgeon on the line of the back of said shear plate which will projecting 45° into the side of said plate so that said shear plate is nearly horizontal & its cutting edge perfectly straight & parallel to the edge of the crop bar. This shear plate being thus hung by its end gudgeons is easily turned up when the cloth is put in to be sheared so as to make it convenient to put the cloth between the said crop bar and said shear into the rollers wider than which feed in the cloth in a regular manner when shearing.

The moving shear is placed over the stationary shear consisting of two or more plates, which form a proper angle with the stationary shear as may be necessary for them to have. When the moving shear moves forward it is raised up and when it is forward it is then pressed down against the stationary shear and moved back when it cuts the knap off of the cloth as is wanted. The plates of the moving shear stand sideways & their width being nearly perpendicular are fixed by means of iron clamps to a crop bar, as the frame which cropbar or shear frame, is fixed to the horizontal pit stones of the cranks that give motion to the moving shear in the manner above mentioned. These two pit or crank stones extend horizontally about seventeen inches from said cranks a little beyond the shear, and the ends thereof are connected by joint pins to two perpendicular arms which arms are at the upper end, fixed by joint pins to a bar extending across from post to post, and the moving shear being, thus fixed firmly into a frame connected to said cranks, has thereby such a motion given to it as to be peculiarly ad.vantagous in shearing cloth, as said cranks always have something of a spring in their operation which prevents the settling of the shear. The joint pins to the

upper ends of said arms, are placed so as to be easily taken out and the moving shear and its frame raised up out of the way when the cloth is first put into the machine to be shaved. The axis of said arms has at each end centers which run in the ends of adjusting screws by which said arms are kept tight. said cranks are formed of a suitable bar of iron so bent near its ends as to form two cranks on the same side of the bar of iron, on one end of this axis a wooden wheel is fixed for the bands by which it is put in motion. The said crank arms are connected to said cranks with proper boxes so made as to be tightened with screws & kept firm, and the crop bar to which the arms connected to said crank arms are fixed, is made to be elevated as depicted so as to bring the edges of the shear together in the same wear way.

A long brush made to revolve on an axis is placed in the frame and its quidgongs go into said parts of the frame of the machine & this brush is turned by a band going round a wheel on one end of the axis of said brush so as to brush the knot of the cloth up to the edge of the shear when it is shaved off. Between this revolving long brush, and the rolling beans on which the cloth is first wound is placed a flat over a crop bar of the frame, and this flat lying upon the cloth, passes it down in said crop bar so as to prevent the cloth from being drawn in to the shear in too slack a manner, at each end of this flat a weight is suspended to give a proper degree of obstruction to the motion of the cloth as the same is drawn into the machine on one end of said rolling beans, a weight is also suspended by a rope which goes round the rolling beans in manner like a band, & this is to obstruct said rolling beans turning round too easily.

The axis of the band wheel which gives motion to this machine is placed over the shear and a little backward of them and the quidgongs run in the upper ends of said parts of the frame. The said wheel on this axis to run this axis

In carrying the said cross shaft and revolving brush, is about a foot in diameter. At the end on said cross shaft about two inches in diameter are so left at the side of this broad wheel shaft the judgment wheel and begins the part of the frame two or three inches wide has four circular eyes put through it so as to take into the holes made in the wide leather band which goes round a large band wheel on the judgment of the same roller which draws in the cloth when shearing. And the calculation here is to have the roller which draws in the cloth the band wheel on the judgment of this roller (and the judgment and eyes in it,) of the great band wheel shaft so proportioned both as to eyes and motion as to have the cloth carried in one sixteenth part of an inch or thereabouts, for every cut or operation of the shear. One of the said rollers which draws in the cloth is hung by its judgment in a frame and so contrived as to have this roller compressed against the other by a spring ~~leg~~ ^{lever} so as to hold the cloth tight between them & be sure of drawing it in as wanted. The lower roller is covered with cloth. A long ~~iron~~ ^{affirm} bar or trough is fixed at the back and a little under the shear to receive the knaps as cut off and keep it from falling down on the cloth after it is sheared. This machine may be carried by water or any other adequate power; And it is to be noted that the end of the plates forming the movable shear run by each other a little so that a complete cutting edge is formed from one end to the other of the shear. The rollers must be turned perfectly round, and true, as also their iron judgments.

All parts of the machine requiring adjustments are contrived with adjusting screws and wedges.

Witness,

John Blanchard
et. al. Fuller
